UNITED STATES PATENT OFFICE

LOGAN WILLARD MULFORD, OF LONG ISLAND CITY, NEW YORK

VAULT LIGHT, FLOOR LIGHT, OR SKYLIGHT

Application filed June 26, 1930. Serial No. 463,955.

The object of this invention is to devise a novel vault light, floor light or skylight construction which will provide greater strength and greater durability than the constructions of the prior art, which will provide a largely increased light area and a greatly decreased weight per square foot, which can be more cheaply manufactured and sold than the constructions heretofore used and which also enables one to use a lighter and cheaper carrying construction.

It has heretofore been the practice in this art to surround the lenses with concrete or to use a reinforced concrete frame, or to use concrete between the metal surrounding the glass. The presence of concrete in a device of this character has been the cause of continuous trouble from leakage, breakage of lenses, and expense in upkeep due to frequent replacement of the broken lenses. Cracks occur in the concrete due to vibration to which the construction is subjected, and leakage occurs due to these cracks or to the non-sticking of the concrete to metal faces of the framework. The expansion of the concrete causes the breakage of the glass lenses and, in the constructions as heretofore manufactured, where the lenses were not surrounded by metal, it was necessary to employ skilled mechanics to chisel out the old concrete and to mix and pour new concrete against the old concrete which was not removed.

In order to overcome these defects in constructions of this character as heretofore manufactured, I have devised a novel vault light, floor light or skylight construction, which can be fabricated from steel bars in order to obtain greater strength and carrying capacity and thus eliminate the necessity of employing reinforcing or carrying members as required with cast iron construction. The steel bars are secured together by welding, galvanizing, caulking or interlocking, in order to form openings conforming to the contour of the lenses, and the steel framework thus formed preferably extends substantially to the top faces of the lenses to contribute with the water proof sealing compound, surrounding the lenses, to form a

non-slipping tread surface. The vault light, floor light or skylight thus formed can be manufactured at the plant in proper sizes to cover the openings which are to be spanned. The water proof cushion preferably consists of a heated tar and sulphur compound. I also eliminate the necessity of employing Portland cement in proximity to the glass or between the metal surrounding the glass.

With the above and other objects in view, as will hereinafter more clearly appear, my invention comprehends a novel vault light, floor light or skylight having a greater glass area and greatly decreased weight.

It further comprehends a novel construction of the character specified, wherein the framework is fabricated from steel bars which may extend to the top of the glass, thus providing a positive protection and shield against breakage of glass from expansion, and the lenses are secured in place by means of a tar and sulphur or other water proof compound which may form, with the exposed portion of the steel frame, a tread portion which is non-slipping.

My invention further comprehends a novel construction of the character herein specified, wherein fabricated steel bars have secured to them, spaced cross members, the main supporting bars and the cross members preferably having grooves or channels to receive the water proof compound which surrounds the lenses.

It further comprehends a novel construction of the character specified, which can be manufactured at the factory and shipped as a unit or in section to the place of installation with a minimum cost of transportation and handling.

My invention further comprehends a novel construction of the character specified having a novel steel framework in which each glass is separately pocketed so that it can be replaced by unskilled labor in a minimum of time and without the necessity of cutting of concrete, without leaving patchwork or the liability to leakage.

Other novel features of construction and advantage will hereinafter more clearly ap-

pear in the detailed description and the appended claims.

For the purpose of illustrating the invention I have shown in the accompanying drawings a typical embodiment of it, which, in practice, will give reliable and satisfactory results. It is, however, to be understood that this embodiment is typical only and that the various instrumentalities of which my invention consists can be variously arranged and organized, and the invention is not limited to the precise arrangement and organization of these instrumentalities as herein set forth.

Figure 1 is a top plan view of a vault light, floor light, or skylight embodying my invention.

Figure 2 is an end elevation of the construction seen in Figure 1.

Figure 3 is a perspective view, partly broken away, of the steel framework.

Figure 4 is a section taken through one of the lenses and two of the main supporting bars.

Figure 5 is a bottom plan view illustrative of one manner of securing together a supporting bar and a T bar.

Similar numerals of reference indicate corresponding parts.

Referring to the drawings:

The supporting framework of the vault light, floor light or skylight is made up of fabricated steel bars, consisting of main supporting steel bars 1 to which cross members 2, illustrated as inverted T bars, are applied to form lens receiving openings 3. The main supporting bars 1 are formed with a lower central web 4 terminating at its lower end in an enlarged base 5. The web 4 merges into flanges 6 which extend laterally from opposite sides of a bar 1, and the top faces of such flanges are preferably provided with longitudinally extending grooves or channels 7. An upper centrally disposed web 8 preferably contributes to form the channels 7 and preferably extends upwardly to the tread surface of the vault light, floor light or skylight construction to form a portion of its tread surface and to contribute to form a non-slipping tread surface.

The T bars 2 have the general contour of an inverted T and have their central webs 9 extending upwardly preferably to the top face of the vault light, floor light or skylight construction to preferably form a portion of its tread surface and to preferably contribute to form a non-slipping tread surface. The T's 2 are provided at opposite sides with laterally extending base flanges 10 having preferably opening through their top faces the grooves or channels 11, the inner side walls of which are formed by the central webs 8.

In order to space the steel bars 1 and 2 together, the central webs 8 of the main supporting bars 1 are provided at spaced in-

tervals with the spaced slots 12 which open through the top faces of the webs 8 to receive the webs 9 of the T bars 2. The T bars are cut out through their base flanges and a portion of their central web 9 as at 13, so that they can be moved downwardly into spacing engagement and bring their base flanges into the same lateral plane as that of the flanges 6 of the main supporting bars 1 and provide a support for the glass lenses 14.

The side walls of the lenses 14 are preferably provided with grooves 15 to provide a locking engagement with the water proof sealing compound 16. This sealing compound preferably consists of a heat treated tar and sulphur compound which is poured around the lenses to fill the grooves or channels 7 and 10 and to extend to the top face of the lenses on opposite sides of the webs 8 and 9 to preferably contribute therewith to form a non-slipping tread surface.

Special attention is directed to some of the novel features of my construction.

The use of steel bars instead of castings and the elimination of the necessity of using concrete provides a lighter weight for shipping and handling, and also provides an increased tensile strength of the framework and of the finished construction.

The object in view, in a construction of this type, is to obtain as large a glass area as possible, and, where concrete has been used, the maximum glass area obtained has been about fifty-six per cent. In my present invention eighty or more per cent glass area is obtainable.

The vault light, floor light or skylight construction can be shipped as a unit or in sections and readily installed by unskilled labor.

The webs of the steel bars which surround the lenses preferably extend to and form a part of the tread surface and may contribute with the sealing compound to form a non-slipping tread surface.

The use of steel bars to carry the load of the construction eliminates the necessity of employing additional carrying members as required with cast iron, and the elimination of the concrete overcomes the breakage of glass and the leakage arising from cracks in the concrete. If a glass is to be replaced the work can be accomplished in a minimum of time by unskilled labor.

My present invention provides a construction having increased strength, durability, and freedom of glass replacements, a greatly reduced weight per square foot and can be manufactured, sold and installed at a cheaper price than the vault lights, floor lights or skylights now in use which can be walked upon.

In so far as I am aware, I am the first in the art to devise a vault light, floor light or skylight construction which can be walked upon, formed of fabricated steel bars without the use of concrete.

Another important feature of this invention is that due to the decreased weight of the construction it is not only cheaper in shipping and handling but it enables the architect or engineer to use a less expensive construction for carrying or supporting the vault light, floor light or skylight.

5 In skylight construction it enables one to use large sheets of glass and thus provide an increased light area.

10 It will now be apparent that I have devised a new and useful vault light, floor light or skylight which embodies the features of advantage enumerated as desirable in the 15 statement of the invention and the above description, and while I have, in the present instance, shown and described a preferred embodiment thereof which will give in practice satisfactory and reliable results, it is to be 20 understood that this embodiment is susceptible of modification in various particulars without departing from the spirit or scope of the invention or sacrificing any of its advantages.

25 Having thus described my invention what I claim as new and desire to secure by Letters Patent, is:—

1. In a vault light, floor light or skylight, 30 fabricated metal bars arranged substantially parallel to provide load carrying capacity, sets of other fabricated bars interconnected at an angle with the other bars to form glass receiving openings, seats on the bars to support the glass within the openings, the glass 35 extending for substantially its entire depth in juxtaposition to the surfaces of the surrounding bars, such bars extending substantially to the tread surface, and a sealing compound surrounding the glass and interposed 40 between it and the bars.

2. In a vault light, floor light or skylight, 45 fabricated metal bars arranged substantially parallel to provide load carrying capacity, sets of other fabricated metal bars interconnected at an angle with the other bars to form glass receiving openings, seats on the bars to support the glass within the openings, and a sealing compound surrounding the glass for its entire height above its support, the bars 50 extending to and forming a part of the tread surface to form with the sealing compound a non-slip tread.

3. In a vault light, floor light or skylight, 55 fabricated metal bars arranged substantially parallel to provide load carrying capacity, sets of other fabricated metal bars interconnected at an angle with the other bars to form glass receiving openings, seats on the bars to support the glass within the openings, the 60 tread surfaces of the glasses being closely juxtaposed to provide a maximum glass tread area and the glass being metal shielded, and sealing compound surrounding the glasses.
